UNITED STATES PATENT OFFICE.

NEVIL MONROE HOPKINS, OF WASHINGTON, DISTRICT OF COLUMBIA.

ANTISKID DEVICE.

1,330,115.

Specification of Letters Patent. Patented Feb. 10, 1920.

Original application filed September 25, 1919, Serial No. 326,199. Divided and this application filed October 22, 1919. Serial No. 332,389.

To all whom it may concern:

Be it known that I, NEVIL MONROE HOPKINS, a citizen of the United States, residing at Washington, District of Columbia, have 5 invented certain new and useful Improvements in Antiskid Devices, of which the following is a specification.

My invention has for its object the prevention of skidding of motor-propelled vehicles having rubber tires. Skidding takes place when the surface of the roadway is 10 wet or greasy. I have found that, by forcibly projecting a stream of granular gritty material such as sand against the rubber 15 tires of a vehicle, the sand will adhere to the tire and because of the thus roughened surface, the tires will not slip or slide on the roadway.

As a means for projecting the gritty material, I prefer to use a motor-propelled fan 20 by which is produced a blast of air to project the sand against the tire. My invention also includes the provision of an automatically actuated valve for controlling the flow of 25 sand to the air blast; means for increasing the velocity of the air blast and other features which will appear from the accompanying description.

My invention will be readily understood 30 by reference to the accompanying drawings in which—

Figure 1 is a vertical section on plane I—I; Fig. 2 is a horizontal section on plane II—II of Fig. 1;

35 Fig. 3 is a plan of Fig. 1;

Fig. 4 shows the device applied to an automobile;

Figs. 5 and 6 are details showing the operation of the sand valve;

40 Fig. 7 is a diagrammatic illustration of a modification.

Referring to the drawings 1 is an electric motor mounted in a casing 2. The shaft 3 of the motor, carries at its outer end, fan 45 vanes 4, 4, preferably made of aluminum or aluminum alloy, so that there may be a minimum of inertia, thus permitting the motor to come to speed as rapidly as possible. The vanes 4, 4 are mounted within a casing

50 5 having an opening 6 (which may be covered with wire netting) to the outer air,

The current of air from the fan is delivered into a duct 7, which preferably has an extension nozzle, 8, which may be detachable and is curved to project the sand against 55 the rubber-tire 20 of the wheel in a substantially tangential direction, as shown in Fig. 4. The sand may be contained in a box 28 from which it is delivered through tube 9 into a hopper 10, which has a depending delivery tube 11, whose lower end is preferably beveled as shown.

Mounted to close the delivery tube is a valve 12, having about its periphery a sand-retaining lip 13. This valve is mounted on 65 a transverse pin or shaft 14 and has a depending flap 15 extending down into the duct 7. This flap 15 is preferably weighted sufficiently to cause it to normally and automatically close the sand delivery opening. 70 This duct is constricted by means of inwardly extending inclined members 16, preferably arranged on the four sides of the duct. The upper member 16 extends at its end into the duct 7 a sufficient distance to 75 prevent the blast of air from directly meeting the valve 12. The contracted form of the duct just in front of the point at which the sand is delivered, causes a concentrated blast of air to carry the sand at a high rate 80 of speed through the duct and deliver it against the rubber tire.

The flap valve, when the device is not in use hangs down in the full-line position and keeps the valve 12 closed. When, however, 85 the blast of air strikes this flap 15, it is raised into the dotted line position and the valve 12 is opened, permitting the sand to flow out of the hopper and into the air blast. It is of importance that the end of the delivery tube 11 be beveled, as shown in Fig. 6, since by this arrangement, even if grains of sand should lodge between the valve and the edge of the tube near the pivot, the valve will still keep the tube closed. If, however, 90 the end of the tube 11 is horizontal as shown in Fig. 5, the lodging of sand will keep the valve slightly open and the sand will flow out as shown, even over the upturned lip of the valve.

100 The sand-hopper 10 may have an additional supply opening 26 (Fig. 1) to which

is connected supply tube 17 (Fig. 3) which may lead to a storage box located within the body of the automobile.

Fig. 7 illustrates a modified arrangement in which the valve 12' is automatically operated by a solenoid, 17, in series or multiple circuit with the motor 1, and the battery 18. An operating switch 19, serves to open and close the circuit. As soon as the switch is closed the motor is started and the valve is moved into open position. When the switch is opened the motor stops and the spring 20 retracts the valve to closed position.

15 The operation of the device will be readily understood from the foregoing description. When the roadway is slippery or greasy, the closing of the electric circuit will cause the motor to operate the fan to produce a 20 blast, whose velocity is increased by the constrictions in the duct. The valve either by the action of the solenoid or by the action of the blast on flap 15 opens automatically, and the sand is driven forcibly against the 25 tire to which it adheres, thus preventing skidding by causing the sanded tire surface to grip the roadway.

While I have referred to sand as the material used, any other suitable gritty or adherent material, such as ashes, sawdust, Portland cement, or a mixture of such substances may be used.

30 My invention is applicable to electrically driven vehicles, as well as to vehicles driven by internal combustion or steam engines.

While I have shown means for delivering sand only onto one wheel, it is obvious that a second duct may be connected to the fan for delivery of sand to another wheel.

40 The motor and fan are shown as mounted horizontally but they may just as well be arranged to have the shaft vertical, and this arrangement is particularly advantageous when two blast tubes are used.

45 The subject matter of this application is related to the subject matter of my co-pending application Serial No. 326,199 filed Sept. 25, 1919.

I claim:

50 1. An anti-skid device for motor vehicles comprising a duct for discharging abrasive material, a fan for ejecting the said material out of the duct, means for actuating the fan and means for feeding the material into the 55 zone of action of the fan.

2. An anti-skid device for motor vehicles comprising a duct for discharging abrasive material, a fan for ejecting the said material out of the duct, means for actuating the fan, 60 means for feeding the material into the zone of action of the fan and means for controlling the said feeding means.

3. An anti-skid device for motor vehicles comprising a duct for discharging abrasive 65 material, a fan for ejecting the said material

out of the duct, means for actuating the fan, means for feeding the material into the zone of action of the fan and means responsive to the action of the actuating means for controlling the said feeding means.

70

4. An anti-skid device for motor vehicles comprising a duct for discharging abrasive material, a fan for ejecting the said material out of the duct, a motor for actuating the fan, means for feeding the material into the 75 zone of action of the fan and means responsive to the action of the motor for controlling the feeding means.

75

5. An anti-skid device for motor vehicles comprising a duct for discharging abrasive 80 material, a fan for ejecting the said material out of the duct, a motor for actuating the fan, means for feeding the material into the zone of action of the fan, a valve for controlling the said feeding means and means 85 constructed and arranged to open the valve when the motor is in operation and to close the valve when the motor is inoperative.

80

6. An anti-skid device for motor vehicles comprising a duct for discharging abrasive 90 material, a fan for ejecting the said material out of the duct, a motor for actuating the fan, means for feeding the material into the zone of action of the fan, a valve for controlling the said feeding means and means 95 responsive to the speed of the motor for controlling said valve.

90

7. An anti-skid device for rubber tired vehicles comprising a motor, a fan driven by said motor, a duct arranged to deliver 100 the blast of air from the fan on to the tire, and a sand receptacle having a valve for permitting sand to flow from said receptacle into said duct.

100

8. An anti-skid device for rubber tired vehicles comprising a motor, a fan driven by said motor, a duct arranged to deliver the blast of air from the fan on to the tire, and a sand receptacle having an automatically 105 actuated valve for permitting sand to flow 110 from said receptacle into said duct.

105

9. In an anti-skid device for rubber tired vehicles, a duct, means for causing a blast to flow therethrough, a sand receptacle having an opening into said duct, a valve for 115 closing said opening, said valve having opening means arranged to be actuated by the blast.

115

10. A device as claimed in claim 9 in which the valve operating means comprises 120 a flap depending into the duct.

120

11. A device as claimed in claim 9 in which the sand receptacle has a delivery tube having a beveled end.

125

12. A device as claimed in claim 11 in 125 which the valve has a sand-retaining lip.

130

13. In an anti-skid device for rubber-tired vehicles, a blast pipe, a sand hopper mounted above said pipe, a delivery tube from said hopper, a flap valve for opening and closing 130

said delivery tube, and constricting means in said pipe arranged to prevent the blast from striking the valve.

14. In an anti-skid device for rubber-tired vehicles, a blast pipe, a sand hopper mounted above said pipe, a delivery tube from said hopper, a flap valve for opening and closing

said delivery tube, said valve having an operating member arranged to depend into the blast pipe, and constricting means in said pipe arranged to prevent the blast from striking the valve. 10

In testimony whereof, I affix my signature.

NEVIL MONROE HOPKINS.
